**COMBINED PACKAGING AND DISPLAY CARTON
FOR A POWER TOOL OR THE LIKE**

Arthur L. Shreve III, Butler, Lyell Bayne Norris, Jr.,
Phoenix, and Robert W. Beichler, Baltimore, Md.,
said Shreve and said Norris assignors to The Black
and Decker Manufacturing Co., Towson, Md.

Original design application June 23, 1969, Ser. No.
17,834, which was a division of Ser. No. 11,599, Apr.
24, 1968. Divided and this application June 8, 1970,
Ser. No. 23,362

Term of patent 14 years

Int. Cl. D9—03

U.S. Cl. D9—191

FIG. 1

FIG. 2

FIG. 1 is a front perspective view of a combined packaging and display carton for a power tool or the like showing our new design; and

FIG. 2 is another front perspective view looking from the bottom of FIG. 1.

The rear, not shown, is substantially a mirror image of the front thereof except that the mounting tabs shown in the lower left of FIGS. 1 and 2 are not present.

This application is a division of application S.N. D.17,834, filed June 23, 1969, now Pat. No. D.219,334 patented Dec. 1, 1970, which was a division of application S.N. D.11,599 filed Apr. 24, 1968, now Pat. No. D.217,131 patented Apr. 14, 1970.

We claim:

The ornamental design for a combined packaging and display carton for a power tool or the like, as shown and described.
